UNITED STATES PATENT OFFICE.

FREDERICK A. MANNING AND FRANK D. FRAZEE, OF SPRINGFIELD, ILLINOIS.

AWNNG-ARM.

1,204,582.

Specification of Letters Patent. Patented Nov. 14, 1916.

Application filed August 20, 1914. Serial No. 857,751.

To all whom it may concern:

Be it known that we, FREDERICK A. MANNING and FRANK D. FRAZEE, citizens of the United States, residing at Springfield, in 5 the county of Sangamon and State of Illinois, have invented new and useful Improvements in Awning-Arms, of which the following is a specification.

Our invention relates to improvements in 10 awning arms, and has for its object the provision of a device of that character, which will provide the supporting means for an awning, and which will extend from the front of a building in a substantially parallel relation with the slope of the awning 15 cover.

Another object is to so construct our awning arm that it will be folded up upon the raising of the awning to its folded or rolled-up position, the arms to lie, when folded, directly under the rolled awning cover against the building.

A still further important object of our 25 invention is to provide means for adjustment, whereby the awning may be given a wide range of slope, varying from a horizontal position to any desired downward pitch usually required in awnings.

With the above, and other objects in view, 30 our invention comprises the novel details of construction and arrangement herein to be described, illustrated in the annexed drawings, and pointed out specifically in the appended claim.

In the accompanying drawings, to which 35 reference will be had, and wherein the preferred embodiment of our invention is illustrated, like characters of reference refer to the like or corresponding parts throughout 40 the several views.

Figure 1 comprises perspective views of our awning arm shown in its working position. Fig. 2 is a side elevation of our assembled arm, also shown in its working relation to an awning cover. Fig. 3 is a top 45 plan view of our assembled arm. Fig. 4 is a sectional view of the spring housing, showing the hinge pin and spring, taken on line 4—4 of Fig. 3.

Our awning arm comprises a stationary 50 hanger 1, which is preferably bolted to the wall of the building directly below the awning roller 30, and which hanger comprises a projecting vertically disposed disk 2. A second disk 3 is bolted to disk 2 by a pivot-

ing bolt 4 passing through the center of the disks. The adjacent faces of the disks are provided with radial meshing teeth 9, and a nut is provided on bolt 4 whereby the disks may be locked in meshed relation. 60

Projecting from disk 3 is a cylindrical spring housing 5, caps 6 being provided on each of the open ends thereof. Disposed above and below caps 6 are parallel lugs 10 and 11, which lugs are provided on the arm-carrying yoke 12, each of said lugs being provided with hexagonal perforations there-through. 65

Numeral 7 designates a hinge pin passing through lugs 10 and 11, caps 6, and cylinder 70 5. Caps 6 are provided with circular perforations to receive the pin 7, which is cylindrical for the portion of its length between the outer faces of caps 6, hexagonal sectioned portions 13 being provided adjacent each end of the pin where it passes through lugs 10 and 11. One end of pin 7 is provided with a head 7', and on the other end is disposed a nut 8. 75

Inside of cylindrical spring housing 5, we 80 provide a coil spring 14 having one end engaged to pin 7 in any suitable manner, as by having the end of the spring engaged in a hole 15 in the pin. The other end of the spring is engaged to housing 5 by being inserted in hole 16 in the housing wall. 85

Arm-carrying yoke 12 is provided with a projection 12' adapted to receive the upper end of strap iron bar 18, bolts being provided to bolt the bar and projection together. The lower lug 11 of the yoke 12 is 90 hinged to the yoke at 17, such means being provided to allow for the assembling of the device.

The central hinge comprises a yoke 12, 95 identical in construction to the yoke 12 in the upper hinge, with the exception that the yoke is reversed, the projection 12' being directed inward to engage the outer end of bar 18. Between lugs 10 and 11 is disposed 100 a cylinder 5, having caps 6 on each end. A hinge pin 7 is passed therethrough and a coil spring 14 is disposed about the pin, one end of the spring being engaged to the pin and the other end engaged to the housing 5. 105

Projecting from the housing 5 is a disk 3, radial teeth 9 being provided on one of the faces thereof. Disk 2 is engaged thereto by bolt 4, and is likewise provided with radial teeth 9 meshing with the teeth of the adja- 110

cent disk. A projection 20 extends outward from disk 2, to which projection the lower strap iron bar 21 is bolted.

The outer end of bar 21 is engaged to 5 front bar 22 of the awning by a hinge, comprising a yoke 23 engaged about the bar 22, and provided with parallel lugs 24. The outer end of bar 21 is twisted to enter lugs 24 at right angles to the upper end of that 10 bar, a hinge bolt 25 pivoting the bar to the lugs.

It will be readily understood that the adjustment for pitch provided in our invention comprises the means for adjustment afforded 15 by disks 2 and 3 in the upper and central hinge units. By loosening the nut on bolt 4 the relative relation of disks 2 and 3 may be readily adjusted for a wide range of pitch.

It is to be understood, that while our awning arm may be used in conjunction with 20 awnings of every variety, yet the necessity of a device of this general character is experienced, when designing awnings on store fronts whereon it is desired to have the awning extend at very little pitch. In such installations side braces are undesirable, and the difficulty of folding the entire awning into a compact space against the wall is encountered. Our awning may be compactly 25 folded, as, when the roller 30 is revolved, in any well known manner, the front bar 23 is drawn directly inward toward the roller, causing the lower section 21 of the arm to force the upper section 18 upward and 30 around its pivoting hinge adjacent hanger 1. (See Fig. 1.) The lower section of arm may be so adjusted for slope as to swing against and above the upper section, the disk 3 in the central hinge being slightly offset from 35 cylinder 5 to allow the lower section of arm to lie closely against the upper section. Both of the sections may thus be adjusted to lie directly under roller 30 in their folded positions. When the awning is lowered,

springs 14 will force the arms outward, the 45 springs being under their greatest tension when the arms are folded, causing the awning to lower easily and quickly even when adjusted for very little pitch.

In order to prevent the straightening of 50 the arms so that they will not fold when the awning is raised, we have provided buffers 18 on the lower lugs 11 of each of the hinges, which buffers are positioned at a predetermined relation with the disks to prevent 55 complete straightening of the arm. By this means, the front bar 23 cannot be lowered to such an extent that the arms will straighten out sufficiently to destroy the leverage about each of the hinge pins. 60

While we have herein described the preferred embodiment of our invention, we do not wish to be limited strictly to the details shown, as it is obvious that the elements of construction and arrangement may be varied 65 in many ways, without departing from the broad spirit of our invention.

Having thus described our invention, what we claim is:—

A spring hinge for connecting the adjacent ends of a pair of bars, one of the bars having associated therewith a cylindrical casing, removable caps for the ends of the casing, a pin extending through the casing and supported by the caps, a spring connecting the pin with the casing, a yoke associated with the end of the other bar and having a rigid and a hingedly connected arm both of which being pivotally engaged with the ends of the pin, and serving to retain the caps on the casing and to permit relative swinging movement of the bars. 70 75 80
